UNITED STATES PATENT OFFICE.

JOSEPH W. DAILEY, OF DETROIT, MICHIGAN.

FASTENING DEVICE FOR DRAFT-PINS.

SPECIFICATION forming part of Letters Patent No. 291,804, dated January 1, 1884.

Application filed May 8, 1883. (No model.)

To all whom it may concern:

Be it known that I, JOSEPH W. DAILEY, of Detroit, county of Wayne, State of Michigan, have invented a new and useful Improvement in Means for Fastening Draft-Pins; and I declare the following to be a full, clear, and exact description of the same, such as will enable others skilled in the art to which it pertains to make and use it, reference being had to the accompanying drawings, which form a part of this specification.

My invention consists in the combination of devices and appliances hereinafter specified, and more particularly pointed out in the claims.

15 In the drawings, Figure 1 is a side elevation of a device embodying my invention. Fig. 2 is a plan view with the latch closed. Fig. 3 is a plan view with the latch opened.

Heretofore in the operation of horse-cars a difficulty has been experienced from the liability of the draft-pin which secures the evener to the draw-bar to work loose. It is the object of my invention to remedy this difficulty by providing simple and economical means where- 25 by said draft-pin may be held firmly in place, while it may also be quickly and readily disengaged whenever it is desired to shift the evener or to remove the pin for any reason. I accomplish this object as follows:

30 In the drawings, A represents the dash-board of the car.

B represents the draw-bar.

C represents the evener.

D represents the draft-pin, constructed, as is 35 usual, with an extended arm, for the ready operation of the driver, said pin being provided with a suitable shoulder, d, suitably located near the top.

E represents my improved fastening, consisting of the jaws e, rigidly secured to the bracket E', said bracket adapted to be secured, by means of bolts or otherwise, upon the dash-board of the car. Near the outer end of the jaws they are suitably expanded to form the orifice e', 45 said orifice communicating with the socket e'.

E' is a latch pivoted between said jaws, and preferably provided with a stopper, e'', adapt- ed to close into the orifice e', the latch prefer-

ably being constructed with shoulders e⁴, for the ready operation of the latch. 50

The operation of the device is as follows: The fastening may be readily secured upon the draft-pin by raising the latch and passing it over the top of the pin, the curved handle d' being left with a suitable opening, d'', for this 55 purpose. The fastening is secured to the dash-board in such a position that the slot e' will rest upon the shoulder d of the pin. The latch being closed, as shown in Fig. 2, it is evident that the engagement of the shoulder d with 60 the edges of the fastening will effectually prevent the pin from being raised or thrown out of engagement with the evener and the draw-bar. Should it be desired to raise the pin, by opening the latch the pin may be drawn back 65 out of the slot e' into the larger orifice e', as shown in dotted lines in Fig. 1, the diameter of the orifice being larger than that of the shoulder d upon the draft-pin, and permitting the pin to be raised through said orifice; and when 70 it is desired to secure the pin in position again the latch is closed behind it, the stopper e'' closing into the orifice e'.

The extending shoulders e⁴ of the latch enable the driver to manipulate the latch with 75 ease.

What I claim is—

1. A fastening for securing draft-pins firmly in place, consisting of suitable embracing-jaws adapted to be secured to the dash-board, and 80 provided with the orifice e', communicating with the expanded orifice e', and, in combination therewith, a latch pivoted between said jaws, and adapted, when closed, to hold the draft-pin firmly in the orifice e', substantially 85 as described.

2. A fastening for holding a draft-pin firmly in place, consisting of suitable jaws provided with the orifice e', communicating with the expanded orifice e', and, in combination therewith, a latch pivoted between said jaws, and provided with a stopper adapted to close into the orifice e', the construction being such that when the latch is closed the draft-pin will be held firmly in the orifice e', substantially as 95 described.

3. The combination, with a dash-board and draft-pin provided with shoulders b , of a fastening consisting of embracing-jaws provided with the orifice e^2 and expanded orifice e' , and, 5 in connection therewith, a latch suitably pivoted between said jaws, the construction being such that when the latch is closed the pin will be held firmly in the orifice e^2 , and in that position be prevented from displacement by the 10 shoulders b beneath the fastening, and by rais-

ing the latch the pin may be drawn upward through the orifice e' , substantially as described.

In testimony whereof I sign this specification in the presence of two witnesses.

JOSEPH W. DAILEY.
